(57) **CLAIM**

The ornamental design for a fencing lanyard as shown and described.

DESCRIPTION

FIG. 1 is a perspective view of a fencing lanyard showing my new design;

FIG. 2 is a rear view thereof;

FIG. 3 is a right side view thereof;

FIG. 4 is a bottom view thereof;

FIG. 5 is a top view thereof;

FIG. 6 is a left side view thereof; and,

FIG. 7 is a front view thereof.

The figures show symbolic breaks in the length of the fencing lanyard. The break lines, as well as any portion of the article between the break lines, form no part of the claimed design.

1 Claim, 3 Drawing Sheets
